FITZHUGH TOWNSEND, OF NEW YORK, N. Y.; JOHN J. TOWNSEND, ADMINISTRATOR, OF SAID FITZHUGH TOWNSEND, DECEASED, ASSIGNOR TO GENERAL RAILWAY SIGNAL COMPANY, A CORPORATION OF NEW YORK.

AUTOMATIC BLOCK-SIGNALING SYSTEM FOR ELECTRIC RAILWAYS.

No. 873,468.

Specification of Letters Patent.

Patented Dec. 10, 1907.

Application filed June 29, 1906. Serial No. 323,976.

To all whom it may concern:

Be it known that I, FITZHUGH TOWNSEND, a citizen of the United States, residing at New York city, county and State of New York, have invented an Automatic Block-Signaling System for Electric Railways, of which the following is a specification.

My invention relates to an automatic block signaling system for electric railways where the propulsion current is alternating, and, broadly stated, consists in impressing a direct current upon each block section of the railway, and utilizing such direct current to control translating devices governing the action of the signals.

The object of my invention is to decrease the cost of installation, of such a signaling system, by doing away with the usual generator for the signaling current and the necessary feeder therefrom.

A further object of my invention is to provide means for controlling the action of the translating devices governing the signals, by direct current impressed upon the block sections, rather than by alternating current as is now generally the case, thereby permitting segregation of the block sections so far as the signaling current is concerned, without the employment of reactance bonds between the sections.

The accompanying diagrams will serve to illustrate my invention:

Figure 1—illustrates a system where the direct current is impressed upon the block sections by means of thermo-generators; Fig. 2—is an enlarged view showing the construction of the thermo-generators; Fig. 3—is an enlarged view showing the construction of the armature of the rotary relay employed in Fig. 1; Fig. 4—illustrates a system where the direct current is impressed upon the block sections by means of a battery, and a parallel type of shielded relay employed; Fig. 5—is an enlarged view showing the construction of the relay employed in Fig. 4; Fig. 6—is a view of a relay such as used in Fig. 4, with three poles; Fig. 7—is a plan view of the relay shown in Fig. 6.

Referring first to Fig. 1: 5 indicates a generator of alternating current, 6, feeder therefrom, 7, 8, traffic rails divided into block sections, X, Y, Z. The rail 7 is divided into sections by means of insulators, 9, and the rail 8

is continuous and serves as the return for the propulsion current.

To excite a direct current difference of potential between the rails 7 and 8, I make use of a thermo-generator, 10, which consists, as is usual, of a series of bars, 10^a, 10^b, of dissimilar metals arranged in alternate relation and secured together at their joints, as, for instance, a bar of bismuth secured to a bar of antimony, the whole series being connected across the track-way; also a heating coil, 11, carried around said bars so as to include a series of points of contact of the dissimilar metals.

I wish it understood that I do not limit myself to the employment of a thermo-generator, as I may use a battery, as shown in Fig. 4, or any other device for exciting a direct difference of potential between the rails 7 and 8. To produce the heating current used within the thermo-generator, and to furnish motor power for operating the signals, I make use of a transformer, 12, having its primary, 13, connected across the feeder 6 and the rail 8. The secondary of this transformer is divided into two coils, 14, 15. The coil 14 is connected to the coil 11, of the thermo-generator, and the coil 15 is connected at one end to contact plate 16, and at the other end to an arm, 17, on the armature of relay 18. The coil 15 includes a solenoid, 19, in which the core 20, connected to the signal, moves. The relay 18 is located, as is usual, at the opposite end of the block from that at which the difference of potential is created. It is connected across the rails 7, 8 of a block, the direct current generating device and the relay thus forming a closed circuit.

The relay shown in Fig. 1 consists of a fixed member, 21, and a movable member, 22. The fixed member has a coil, 23, which is in series with a coil, 24, on the movable member, and these two coils are connected across the trackway, 7, 8. The movable member also has a closed circuited coil, 25. The purpose of the closed circuited coil 25 is to counteract the effect of any alternating current which would pass from the track rails into the fixed and movable members of the relay, and which would tend to rotate the relay in the absence of such coil. The theoretical considerations involved are as

follows: The short-circuited coil, 25, tends to exclude any alternating magnetic flux which might be set up by alternating current in coil 23 on account of the induced currents 5 set up in such short circuited coil, and which act as counter-magneto motive forces, opposing the alternating magneto-motive force of coil 23. Also, the coil 25, owing to its induced currents will exert a counter torque, 10 so as to further neutralize the rotative effort, due to the alternating current traversing coils 23 and 24. It will of course be evident that the direct current and magnetic flux after they are once established, will not be 15 affected by the action of the coil 25.

In Fig. 4 both traffic rails are divided into block sections by insulators 9. In this case the rail 7 of one section is connected through a conductor, 26, to the rail 8 of the next section, reversing from block to block, so that instead of the rail 8 acting as the return for the propulsion current, as in Fig. 1, sections of rails 7 and 8 act as the return for the propulsion current. In this figure, as before 20 stated, a battery, 27, is substituted for the thermo-generator as a means for exciting a direct current difference of potential between the rails 7 and 8. Further, instead of using the relay 18, I may use the relay 30, 25 which, while it corresponds in principle with the relay 18 so far as relates to being operable only by a direct current, is different in construction. This relay consists, of an iron core, 31, preferably not laminated, surrounded 30 by a copper shield, 32, and a coil, 33, connected across the trackway. The coil 33 may be surrounded by an iron tube, 34, and a movable member, 35, which consists of an iron core, 36, surrounded by a copper shield, 37, and carrying a depending contact plate, 38, adapted to contact with the contact plates 39, 40.

Figs. 6 and 7 show a modified form of the relay 30, where, instead of using a single core, 31, three cores 41, 42, and 43, are employed. In this form of relay, a resistance, 44, is placed in circuit of the coil surrounding the core 43, and is designed to displace the phase of any alternating current flowing through 45 this coil from the alternating current flowing in coil 41.

The form of relay shown in Fig. 6 has the advantage, by reason of the arrangement of its cores, of preventing chattering of the movable member 35. The theoretical considerations involved are as follows:

The shield 32 is in the form of a short circuited coil which may be of any desired number of turns. If an alternating current 60 flowed in the coil 33, it would normally produce an alternating magnetic flux, but the coil 32, which is short circuited will then develop induced currents, which act as counter magneto-motive forces effectively damping 65 out any alternating magnetism. The

closed iron tube 34 forms a magnetic path closed on itself and surrounding the coil 33, so that any alternating current in such coil will set up an oscillating magnetic flux in the iron tube, producing thereby a counter electro-motive force in the windings of the coil 33, thereby tending to exclude any alternating current from such coil. The action of the tube 34 is the same substantially as the insertion of reactance in series with the coil 33, and it will be obvious that a reactance could be connected in series with the coil 33 if desired. The reactance effect described is, of course, not essential. The shield, 37, is similar in its action to the shield 32. It is 70 some times found that an alternating magnetic flux not sufficient to actuate the relay may, however, occasion a chattering of the contact. This is obviated by causing such magnetic flux to have a different phase in 75 different branches of the magnetic circuit. For this reason, in Fig. 6, the phase of the magnetic fluxes is made different in the coils 41, 42, and 43. On account of such difference in phase the tractive effort due to the 80 alternating current is rendered more even, thereby doing away with any chattering.

The general operation of my system is as follows: When a car is in a block, the wheels of the car short circuit the relay, and the 95 signal being counter-weighted goes to the "danger" position, the position of the relay being that shown at "Z", Figs. 1 and 4. When a car leaves a block, the direct current impressed upon the block flows through 100 the relay, rotates the movable member, Fig. 1, or elevates the movable member, Fig. 2, and thus closes the circuit through the secondary coil 15 of the transformer 9, which by solenoid 19 attracts core 20, and moves 105 the signal to the "clear" position, as illustrated in blocks X and Y, Figs. 1 and 2.

I wish it understood that I do not limit myself to the particular arrangement of the trackway described, or the special construction shown for the relays, as various modifications may be made. Thus I may employ both rails of the trackway for the return of the propulsion current, in which case the resistance of the translating device, 18, Fig. 1, 110 would be made low and also that of the source of E. M. F. energizing the block section. Similarly, where one rail alone is used for the return of the propulsion current, reactances might be inserted both in series with the source of E. M. F. at the energy end and with the translating device at the opposite end of the block section. Various methods of connecting the elements of the system will at once occur to those skilled in the art. Also 115 I may vary the arrangement of the system as by using a direct current for heating the thermo-generator and actuating the signals. Generally, I wish to have it understood that I consider myself to be the first to described. 120 125 130

relay and the use of a relay in a signaling system, which, while susceptible to the flow of direct current, is not susceptible to the flow of alternating current where both currents 5 traverse the relay at the same time.

Having thus described my invention, I claim:

1. A signaling system comprising a source of alternating power current, a trackway 10 divided into block sections, both of the rails of which are traversed by the power current on its return to the generator, means for exciting a direct current difference of potential 15 between the rails of each block, and a relay connected across the rails of each block operable by direct current but not by the alternating power current.

2. A signaling system comprising a source of alternating power current, a trackway divided 20 into block sections, both of the rails of which are traversed by the power current on its return to the generator, means for exciting a direct current difference of potential between the rails of each block, and a relay connected 25 across the rails of each block operable by direct current but shielded from the alternating power current.

3. A signaling system comprising a source of alternating power current, a trackway divided 30 into block sections, both of the rails of which are traversed by the power current on its return to the generator, means for exciting a direct current difference of potential between the rails of each block, a relay in each 35 block having its field and armature directly connected across the rails of the block and said relay operable by a direct current but not by an alternating current.

4. A signaling system comprising a source of alternating power current, a trackway 40 divided into block sections, both of the rails of which are traversed by the power current on its return to the generator, means for exciting a direct current difference of potential 45 between the rails of each block, and a rotary relay connected across the rails of each block operable by direct current but not by alternating power current.

5. A signaling system involving block sections, comprising an alternating current generator for the propulsion current, thermo- 50 generators for exciting a direct current difference of potential between the rails of the block sections, and a translating device energized by the direct current in each block section.

6. A signaling system involving block sections, comprising an alternating current generator for the propulsion current, a thermo- 60 generator in each block for creating a direct current difference of potential between the rails and consisting of a series of bars of dissimilar metal connected together and connected across the trackway, with means for heating the joints, and a translating device

in each block section energized by the current derived from said thermo-generators, but unaffected by the current from the alternating current generator.

7. A signaling system comprising a source of alternating power current, a trackway divided into block sections, both of the rails of which are traversed by the power current on its return to the generator, means for exciting a direct current difference of potential 70 between the rails of each block, and a relay connected across the rails of each block traversed both by the power current and said direct current, together with means for nullifying the effect of the power current on the 75 relay.

8. A signaling system comprising a source of alternating power current, a trackway divided 80 into closed-circuited block sections, both of the rails of which are traversed by the power current on its return to the generator, means for exciting a direct current difference of potential 85 at one end of each block, and a relay connected across the rails at the opposite end of each block operable by the 90 direct current only.

9. A signaling system comprising a source of alternating power current, a trackway divided 95 into closed-circuited block sections, both of the rails of which are traversed by the power current on its return to the generator, means for exciting a direct current difference of potential at one end of each block, and a selective relay device at the other end 100 of each block section, said relays normally actuated by the difference of potential across the rails of the block in which they are included.

10. A signaling system comprising a source of alternating power current, a trackway 105 divided into closed-circuited block sections, both of the rails of which are traversed by the power current on its return to the generator, means for exciting a direct current difference of potential at one end of each block, 110 a selective relay connected across the opposite end of each block, and means for shielding said relays from the effect of any current other than that due to the difference of potential 115 between the rails of the block in which they are included.

11. A signaling system comprising a source of alternating power current, a source of direct signaling current, closed-circuited block sections, both of the rails of which are traversed 120 by the power current on its return to the generator, and relays operable only by the direct signaling current.

12. In a signaling system of the type described, a signal controlling device normally energized by the direct current, means for shielding it from the action of alternating current, and means for preventing chattering of the movable member of such device.

13. A signaling system comprising a 130

- source of alternating power current, a track-way divided into closed-circuited block sections, both of the rails of which are traversed by the power current on its return to the generator, means for exciting a direct current difference of potential between the rails of each block, and a relay connected across the rails of each block operable by direct current but not by the alternating power current.
14. A system of signaling comprising a source of alternating power current, a track-way divided into closed-circuited block sections, both of the rails of which are traversed by the power current on its return to the generator, means for impressing a direct current upon the rails of the block sections, and a relay connected across the rails of each block section operable only by said impressed current.
15. A signaling system comprising a source of alternating power current, track rails divided into block sections, cross bonds in each block section, means excited by the power current for exciting a direct current difference of potential between the rails, and a relay connected across the rails of each block and operable only by the direct current.
16. A signaling system comprising a source of alternating power current, a track-way divided into block sections, cross bonds in each block section, each composed of a series of dissimilar metals, means excited from the power current for exciting a direct current difference of potential between the rails, and a relay connected across the rails of each block operable by direct current only.
17. A signaling system comprising a source of alternating power current, a track-way divided into closed-circuited block sections, both of the rails of which are traversed by the power current on its return to the generator, means for exciting a direct current difference of potential located at one end of each block section, and a relay connected across the rails at the opposite end of each block section, and a signal controlled by said relay.
18. A signaling system comprising a source of alternating power current, a feeder therefrom, a trackway divided into block sections, a thermo generator bond connected across the trackway, a transformer connected across the feeder conductor and one rail and having a divided secondary, one portion connected to a coil on the thermo bond and the other portion to the terminals of a local circuit, and a relay connected across the rails of each block operable by said direct current and adapted to normally close the terminals of the local circuits to carry signals to the "clear" position.
19. In a system of automatic signaling, the combination of sources of direct current for the track circuits, a relay device in each block section operated from the track circuit having a short circuited excluding coil.
20. A signaling system comprising a source of alternating power current, a track-way divided into block sections, means for exciting a direct current difference of potential between the rails of each block section, a relay connected across the rails of each block section, said relay comprising a fixed member having a coil thereon and a movable member having a coil thereon in series with the coil of the fixed member and a closed-circuited coil, the coils which are in series traversed by a direct and an alternating current, and the closed-circuited coil having a current induced therein by the alternating current traversing the series coil, and signals controlled by said relays.
21. In a signaling system wherein the power current is an alternating current flowing along the rails and the signaling current a direct current impressed upon the rails, relays comprising two members, one fixed and the other movable, each of said members having a coil in series with a coil of the other member and connected across the trackway and the movable member having a closed-circuited coil, and signals controlled by said relays.
22. In a signaling system wherein the power current is an alternating current flowing along the rails and the signaling current a direct current impressed upon the rails, relays connected across the track rails through the members of which both currents flow, and a closed-circuited coil on the movable member of the relays adapted to nullify the influence of the alternating current flowing through said relays, and signals actuated by said relays.
23. In a signaling system wherein the power current is an alternating current flowing along both rails of the trackway as a return to the source, and where the signaling current is a direct current creating a difference of potential between the rails, a relay adapted to be traversed by said power current and signaling current, but to be actuated only by the direct current, together with means for neutralizing the effect of the power current transmitted.
24. A signaling system comprising a source of alternating power current, a trackway divided into block sections, a thermo bond in each block section, means for exciting said thermo bond to produce a direct current difference of potential between the rails of each block, and a relay connected across the rails of each block traversed by the power current and by the direct current, together with means for neutralizing the effect of the power current transmitted through the relay.
25. A signaling system comprising a source

of alternating power current, a trackway divided into block sections, said trackway forming a return for the power current and having an alternating difference of potential 5 due to the power current, means for exciting a direct current difference of potential between the rails, and relay devices through which both the power current and the direct current are flowing, together with means for 10 neutralizing the effect of the power current, and signals controlled by said relays.

26: A signaling system wherein there is an alternating difference and a direct current

difference of potential between the rails due to the alternating current flowing along the 15 rails and the direct signaling current impressed upon the rails, and where the relay is traversed by both currents but only susceptible to one.

In testimony thereof, I affix my signature, 20 in the presence of two witnesses.

FITZHUGH TOWNSEND.
